CATCH BASIN

Filed March 5, 1929

HARRY HAYLEY
INVENTOR.

BY *Harold Shipman*
ATTORNEY.

UNITED STATES PATENT OFFICE

HARRY HAYLEY, OF HURDMANS BRIDGE, ONTARIO, CANADA

CATCH BASIN

Application filed March 5, 1929. Serial No. 344,501.

This invention relates to catch-basins and particularly to the outlet to a drain pipe leading to the sewer.

An object of my invention is to provide a catch-basin, formed of a plurality of sections which, when fitted together, embody a discharge by-pass from the receiving chamber up to the outlet to a drain pipe leading to the sewer.

10 A further object is to provide a clean-out opening, communicating from said receiving chamber and providing easy access to said drain pipe and said discharge by-pass.

A further object of my invention is to provide 15 a catch-basin, formed of a plurality of sections which, when fitted together, embody a discharge by-pass from the receiving chamber up to the outlet to a drain pipe leading to the sewer and a clean-out opening at a 20 higher level than the bottom edge of the outlet, yet in such alignment with said drain pipe as to permit horizontal manipulation of rods from the receiving chamber for cleaning out said drain pipe.

25 With the foregoing and other objects in view as will appear as the description proceeds, the invention consists of the novel construction, combination and arrangement of co-operating elements as hereinafter more 30 specifically set forth, claimed and shown in the accompanying drawing forming a part of the present application.

The accompanying illustration discloses a 35 cross-sectional view of the preferred embodiment of my invention.

In the accompanying drawing, I have shown four sections A, B, C and D, which are substantially of hollow tile formation and may be made of any desired material suitable 40 for the purpose, the different sections being provided with interlocking connection.

The section D is provided with a bottom E. The sections A, B and C have at one side an outwardly protruding portion S in which is 45 formed a discharge by-pass F, the lower end of which (as at G) communicates with the central receiving chamber H below the normal fluid level thereof, which level is indicated as at I. J is a clean-out opening formed 50 above the normal fluid level I and preferably

in vertical alignment above the lower end G of the by-pass F. The by-pass F and the clean out opening J jointly communicate with the discharge opening K. This discharge opening K is provided with an enlarged receiving socket for receiving the end 55 of the drain pipe L, which drain pipe L leads to the sewer. Around the clean-out opening, I provide a casing M, having a door N suitably hinged in combination therewith to normally close the clean-out opening J.

In the illustration annexed herewith, it will be noted that the lower edge O of the clean-out opening J is above the lower edge P of the discharge opening K, yet at the same time below the upper edge Q of the discharge opening K. On account of this relative position of the respective openings and by-pass, the surface fluid in the central receiving chamber H will normally flow up through the discharge by-pass F and off through the drain pipe L to the sewer. Under normal conditions the sediment will settle in the section D. When the sediment fills up to a level above the opening G into the by-pass F, the flow of fluid will be cut off. The door N (normally closed) will stop any flow of fluid through the clean-out opening J. The surface water from the street coming into the catch-basin will fill the central receiving 70 chamber. Eventually, one of the civic employees will remove the accumulated sediment, which when removed will allow the sediment in the discharge by-pass F to back-flow into the central receiving chamber H. 75 If this sediment is packed too solidly or frozen in the by-pass F, the employee may open the door N and insert a clean-out tool or steam line.

From the experiments which I have made, 90 there is little or no possibility of the drain pipe L becoming clogged with solid sediment or foreign matter, but if such should be occasioned at any time, my disclosure provides a clean-out opening J, the lower portion 95 of which is in horizontal alignment with the upper portion of the drain pipe F, so that in this way ready access may be had for using the required tools or rods for the cleaning out of the drain pipe L.

A further advantageous feature of my construction is that the central receiving chamber is preferably of annular formation and has no inwardly projecting parts, elbows or connections which would obstruct and hinder the proper cleaning out of sediment or foreign matter from the bottom sections of the catch-basin.

In the sections A, B and C shown in the illustration, I have disclosed what I consider the formation of the different openings and the discharge by-pass in a manner which would be the easiest for casting. These openings and the by-pass may be formed in other relative positions from that disclosed in the illustration without departing from the spirit and scope of the invention as claimed. It may be found advantageous to have these openings and the by-pass cast as a separate unit to be fitted onto the side of a catch-basin, which is in use at the present time so as to transform it into a discharge trap system with clean-out facilities similar to that disclosed hereinbefore.

The foregoing specification and annexed drawing disclose the preferred embodiment of my invention, but it is to be understood that minor changes may be resorted to in the commercial adaptation of my invention without departing from the scope of the invention as hereinafter claimed.

What I claim as new is:

As an improved article of manufacture, a catch-basin of separately moulded, interlocking sections adapted to be built upon each other to make a complete unit, one of said sections providing a closed bottom for said unit, one of said sections having an integral lip outwardly formed at one side thereof, another of said sections having an integral portion outwardly formed at one side thereof and adapted to register in interlocking engagement over said lip, another of said sections having an integral cap outwardly formed at one side thereof and adapted to register in interlocked engagement over said portion, a drain-pipe opening being formed inwardly of the outer contour of said portion and said cap at the junction thereof, a by-pass opening formed in communication with said drain-pipe opening, downwardly through said portion and communicating with the interior of said unit at the junction of said portion and said lip, a clean-out opening formed in said cap at its junction with said portion and communicating from the interior of said unit to said drain-pipe opening and with the upper end of said by-pass opening and a closure member for normally closing the inlet to said clean-out opening.

In testimony whereof, I affix my signature.
HARRY HAYLEY.
